UNITED STATES PATENT OFFICE.

JOHN C. BLEVNEY, OF NEWARK, NEW JERSEY, ASSIGNOR TO THE CORK INSERT COMPANY, OF BOSTON, MASSACHUSETTS, A CORPORATION OF MAINE.

POLISHING DEVICE.

1,094,361.

Specification of Letters Patent. Patented Apr. 21, 1914.

Application filed September 19, 1912. Serial No. 721,315.

To all whom it may concern:

Be it known that I, JOHN C. BLEVNEY, a citizen of the United States, residing in Newark, county of Essex, and State of New Jersey, have invented an Improvement in Polishing Devices, of which the following description, in connection with the accompanying drawings, is a specification, like letters on the drawings representing like parts.

This invention relates to a polishing device and is herein shown as embodied in a polishing wheel, and has for its object to provide an inexpensive and highly efficient wheel of the character described, which is capable of being used for polishing articles of metal, leather or other material. To this end the wheel, which may be of wood, metal or other firm or rigid material, is provided on its periphery with projecting yielding members or devices, which are spaced apart to provide the periphery of the wheel with a series of high and low points, the high points being provided with a suitable polishing or abrading material such as emery, rouge, etc., with which the polishing is effected, and the circumference of the wheel forming the low points which afford ample clearance between the article being polished and the circumference of the wheel, to allow the fine particles of metal or other material detached in the act of polishing, to be removed from the article or work and from the high points of the wheels, whereby the polishing parts of the wheel, to wit, the high points thereof, are maintained in their most effective working condition, with the result that a greater amount of work may be performed at a minimum expense. The high points of the polishing wheel may be made of leather or other fibrous material, but I prefer to employ pieces of cork in its natural state, as the latter not only possesses the property of yielding, but is more or less porous and affords an excellent carrier for the finely divided polishing material, which is thus retained on the wheel and enables the latter to do a maximum amount of work with the greatest efficiency.

Figure 1 is a vertical circumferential section of one form of polishing wheel embodying this invention, the section being taken on the line 1—1, Fig. 2. Fig. 2, a plan view of the wheel shown in Fig. 1. Fig. 3, a plan view of a modified form of polishing wheel

embodying the invention, and Fig. 4, a detail on an enlarged scale to be referred to.

Referring to the drawing, *a* represents a wheel of any ordinary construction and of a size suitable for the particular polishing work to be performed. The wheel *a* may be of metal, wood or other rigid material and has its rim *b* provided with a plurality of yielding devices or members *c*, which project beyond the rim to form a plurality of high points with relation to the circumference thereof. The projecting devices *c* are spaced apart so as to form spaces or clearance openings *d* into which the fine particles of material detached from the article being polished may pass and be thereby removed from contact with the work.

The projecting devices *c* may be of any suitable yielding material, such as leather, felt, etc., but it is preferred to employ cork in its natural state, which may be circular in form as shown in Figs. 1, 2 and 4, and inserted under compression in suitable sockets or openings *e* in the rim of the wheel, or said cork devices may be made in the form of strips which are arranged in suitable slots or elongated openings in the rim of the wheel, as shown in Fig. 3. The abrading or polishing material may be of any suitable or desired material, such for instance as emery, corundum, rouge, etc., and is represented by the stippling. The abrading or polishing material may be affixed to the cork or other yielding working members *c* by glue or other adhesive material, and in practice, the adhesion of the abrading material may be effected by mixing the abrading or polishing material with glue and then rolling the wheel in this mixture, so that the cork or other yielding members are covered with the mixture. By this method, the circumference of the rim is also covered with a thin layer of the mixture, which remains inactive, as it is below the active surfaces of the yielding members and does not contact with the work being polished. The cork members are more or less porous and permit of the fine abrading material being pressed therein and thereby firmly attached thereto, with the result that a more lasting and efficient polishing surface is obtained.

Instead of the particular method of applying the abrading material to the working members of the polishing wheel, any other

desired method may be employed, as for instance the mixture of abrading material and glue or other adhesive may be applied to the cork or other working members with a brush.

In operation with the polishing wheel herein shown, the latter is mounted on a suitable shaft or arbor and is designed to be rotated at a substantially high speed, and the outer surfaces of the projecting working members are engaged with the work to be polished, which may be metal, leather, wood or other material. It will be observed that the projecting devices or working members which carry the abrading material, yield under pressure and afford a substantial surface contact for engagement with the work which is withdrawn substantially in an instant, and is followed by a clearance space into which passes the fine particles of the material which is removed by the abrading material, thereby avoiding contact of the fine particles with the work and the succeeding projecting member. As a result, the polishing wheel is maintained in its most effective condition and its life materially prolonged, whereby a maximum amount of work can be performed at a minimum expense. The cork members also serve to increase the life and efficiency of the wheel and enable a maximum amount of work to be polished at the least possible expense.

Claims:

1. In a device of the character described, in combination, a wheel having a rim of rigid material, a plurality of yielding members projecting from said rim and arranged transversely thereof in substantially close proximity to one another and separated by spaces, which extend transversely of the rim between adjacent yielding members, and abrading material affixed to said yielding members, substantially as described.

2. In a device of the character described, in combination, a wheel having a rim of rigid material provided with a plurality of sockets or openings in it which are arranged transversely of the rim and spaced apart, cork members in said openings and projecting beyond the circumference of the rim to form a succession of high points extended transversely of the rim of the wheel and separated by transversely extended spaces, and polishing material affixed to the outer surfaces of said corks, for the purpose specified.

In testimony whereof, I have signed my name to this specification in the presence of two subscribing witnesses.

JOHN C. BLEVNEY.
